UNITED STATES PATENT OFFICE.

PATRICK H. TOBIN, OF DENISON, TEXAS.

REICING CARS.

1,140,215.

Specification of Letters Patent. Patented May 18, 1915.

Application filed August 24, 1914. Serial No. 858,405.

To all whom it may concern:

Be it known that I, PATRICK H. TOBIN, a citizen of the United States, residing at Denison, in the county of Grayson and State 5 of Texas, have invented certain new and useful Improvements in Reicing Cars, of which the following is a specification.

My invention relates to a means for reicing the refrigerator cars of a railway system in a simple and effective manner and with considerable less time and expense than is now required; and the invention consists, essentially, of a re-icing car which serves as a storage receptacle for block-ice and is 10 adapted to be coupled to a switch-engine, or to be otherwise propelled, so that it may be run on a track alongside and parallel with refrigerator cars to be re-iced, to supply the bunkers of the latter with a fresh supply of 15 ice, said re-icing car having means for elevating blocks of ice from its interior to a point above the roof of the car and at such elevation that the ice may be readily conveyed from the elevator into the bunkers of the adjacent car; and crushing apparatus 20 to which the blocks of ice may be fed, and the ice crushed and reduced to suitable size previous to being discharged into the ice-bunkers of the car to be iced.

My invention further consists of the parts and constructions, arrangements and combinations of parts which I will hereinafter describe and claim.

In the accompanying drawings forming 35 part of this specification and in which similar reference characters indicate like parts in the several views; Figure 1 is a side elevation of a portion of an icing-car embodying the salient features of my invention, showing 40 parts broken away. Fig. 2 is an end view of the same.

The purpose of this invention being to provide an icing-car adapted to operate over a track which is parallel with the train of 45 refrigerator cars to be iced, say at some station on its route, or whenever the supply of ice is depleted to such an extent that the refilling of the ice bunkers of said car becomes imperative, I construct the car, A, of stand- 50 ard size and supply it with those accessories with which the ordinary freight car is usually provided, including a train pipe, a, connecting with the steam-line and a pipe, b, connecting with the air-line so that when 55 the ice-car is coupled to a switch engine, the power derived from the engine through the

train-pipe hose, using either air or steam, may be utilized for operating the several features of my apparatus, which I will presently describe.

Upon the roof of the car and occupying substantially the entire width thereof, is a superstructure which includes a horizontal lower platform, B, suitably supported on and secured to cross beams, C, fixed to the roof, whereby the platform is elevated a slight distance above the roof. The platform is also rigidly connected to suitable uprights, D, at the front and rear corners, and diagonal and other cross-bars, E, brace and 60 make the superstructure rigid.

Upon the top of the uprights, D, is a platform, F, upon which the blocks of ice elevated from the interior of the car, as I will hereinafter describe, are received and down 65 which platform these blocks of ice are caused to gravitate, or be pushed toward an opening, G, in the central portion of said upper platform, said opening having downwardly converging walls, g, forming a hopper 70 for directing the blocks of ice into the hopper end of a suitable crusher, H.

The crusher comprises a frame or casing of suitable form, whose base is supported on and secured to the base or lower platform 85 of the superstructure before mentioned, said casing having mounted within it a shaft, I, on which is fixed any desired form of crushing roll, J, for reducing the ice-cakes into pieces sufficiently small to be used for recharging the bunkers of the usual refrigerator car, and said crusher casing or frame having an opening, K, on one side communicating with a suitable chute, L, preferably of the telescopic order, that is, formed 90 of sections which slide one within the other, and said chute being of sufficient length to extend from the outlet of the crushing machine to the ice-bunker of a refrigerator car 95 on an adjacent parallel track, whereby the output of the crushing machine is immediately discharged through the chute into the bunker of the car to be re-iced. When this operation has been effected, the chute may, if desired, be collapsed or its sections 100 slid together, and the icing-car with its crushing outfit and storage of ice may be moved, by a switch engine or otherwise, into a new position, say alongside of the next refrigerator car of the train to be re-iced, 110 when the operation is again performed in the manner before described.

The icing car being of standard size, has a large holding capacity and hence it serves as a storage reservoir for the blocks of ice which are used in re-icing the refrigerator cars; and in order to expedite the recharging of the bunkers of the refrigerator cars, and to perform this operation with as little expense as possible and with great rapidity, I have provided means for elevating the blocks of ice from the interior of the car to the upper platform, F, of the car-roof superstructure so that the blocks are taken directly from the car and immediately sent to the crushing apparatus, and the crushed ice 10 immediately delivered into the bunkers of the car to be re-iced. By handling the ice in such an expeditious manner there is but little time lost in the re-icing operation and little or no chance of ice waste by exposure 15 or otherwise. Any suitable elevating mechanism may be employed for removing the cakes of ice from the interior of the car to the receiving platform, F, of the car-roof superstructure before mentioned. In the 20 present drawings I have shown an elevator which consists of suitable uprights, M, fixed to the floor of the car and projecting through a hatch-way or opening, N, in the roof of the car, said uprights, being arranged parallel with each other to form a guideway and extending to such height above the receiving platform of the roof superstructure as to insure the proper handling of the ice cake and the ready delivery of the same upon the receiving 25 platform, F.

Within the guideway formed by the parallel uprights, M, suitable cages or lifts, O, are designed to operate, said cages or lifts being connected to appropriate ropes or 30 cables, P, which pass upwardly over suitable guide pulleys, Q, mounted in the upper portion of the framework formed by the aforesaid uprights and suitable cross bars, M'.

In the drawings I have shown two elevators, one placed alongside of the other and each constructed as before mentioned, which arrangement permits me to handle the ice with rapidity, but it will be understood 40 that the arrangement and specific character of the ice-elevator may be greatly modified without departing from the spirit of my invention; and that the elevator shown in the drawing is but illustrative of 45 any means for elevating the blocks of ice from the interior of the icing car to the receiving platform of the roof superstructure.

In Fig. 1. I show mounted upon the lower platform, B, of the frame or superstructure 50 built upon the top of the car, an engine, R, for operating the elevator and which engine has its piston rod, R', connected to the crank of a winding drum, S, over which the cable leading from the cages, O, may be directed in any suitable manner; said engine

may, if desired, obtain the power necessary to operate it from the air-train pipe of some car in the train, but it will be evident that other and different forms of motor, or motive power may be used for operating the 55 ice-elevator, without departing from the spirit of my invention. Suitable means will also be provided on the car for operating the ice crusher.

In Fig. 2 I show on the end of the crusher 60 shaft, I, a band wheel, T, from which a belt, U, passes around a similar wheel, V, and the shaft of a suitable gas or other engine, W, located within the car near one end and suitably supported upon the floor of said 65 car. This engine may be typical of any motor operated by any means and from any source of power, for operating the crushing machine.

The general operation of the icing-car is 70 substantially as follows: The ice-car operating with the ice-crusher and ice-elevator and having its supply of ice in cake-form, is coupled to an engine, and to this end the connection may be such that the power for 75 operating the crusher and the elevator may be derived from the air or steam supply from the engine, although these features are not claimed and formed no essential part of the present invention. If a switch engine 80 is not available then the gasoline engine, W, may be used for the purpose of operating the crusher and elevator.

When the car is being operated it is placed on a track parallel with the train of 85 refrigerator cars which is to be iced. It is run alongside of a car requiring re-icing so that the chute from the crushing machine will stand substantially opposite the ice-bunkers of a car in the train to be iced, 90 whereby the chute from the ice-car extends over and bridges the space between the two cars and reaches over and is adapted to deliver the crushed ice into the mouth of the ice-bunker of the car to be iced. If crushed 95 ice is not desired for the bunker of the refrigerator car, the cakes of ice may be sent to the refrigerator car direct through the chute or otherwise. If crushed ice is desired for the bunkers of the refrigerator car, 100 the cakes of ice are successively placed upon the cages of the elevator and elevated through the roof of the car to such position that they may be delivered onto the upper 105 platform of the superstructure, from whence they are directed into the hopper of the ice-crusher, within which crusher they are reduced and the crushed ice delivered 110 into the chute and at once gravitates therethrough into the bunker of the car to be iced. When the bunker at one end of a car 115 is filled the ice-car is moved to the other end of the refrigerator car, and the chute from the crushing machine is placed in position to deliver ice into the second-named 120

bunker, which is filled in the manner before described. This operation occurs throughout all of the cars of the refrigerator line or such of the cars thereof as may require re-icing.

By handling the ice in the manner described, the loss in waste of ice is practically avoided; there is a great saving in time of re-icing the cars; the expense of re-icing a car is reduced to a minimum, and the re-icing operation is performed with safety. I am also able to re-ice a car without disturbing it from a made-up train, as the ice-car is a storage car and may be run up alongside of the car to be re-iced without disturbing in any manner this latter car.

Having thus described my invention what I claim as new and desire to secure by Letters Patent is:-

1. Means for re-icing a refrigerator car or the like while in position on a railway track, said means including an icing car adapted to travel on a track which is parallel to that on which the refrigerator car is mounted, said icing car having a roof structure provided with an elevated ice-receiving platform; means for elevating the cakes of ice from the interior of the car to said elevated ice-receiving platform; means for crushing the cakes of ice, said ice-crushing means being supported on the roof of the car and directly receiving the cakes of ice from said platform; and means adapted to extend from said car to a car on an adjacent parallel track for conveying the crushed ice from said crushing means to the ice bunkers of said adjacent car.

2. Means for re-icing a refrigerator car or the like while in position on a railway track, said means including an icing car adapted to travel on a track which is par-

allel to that on which the refrigerator car is mounted, said icing car having a roof provided with an elevated ice-receiving platform; an elevator mounted in the car and extending through the roof thereof to a point above and adjacent said platform; an ice-crusher mounted on said platform having an ice-inlet connecting with said platform, and having an outlet for crushed ice; and a chute connecting with the outlet of the crusher and adapted to bridge the space between the icing car and the bunkers of the refrigerator car to be re-iced.

3. A railway icing car having a framework or superstructure on the roof thereof, said framework including an elevated ice-receiving platform, an elevator within the car operating through the roof thereof and extending to a point above said platform, and a chute or runway leading from said frame and adapted to bridge the space between the icing car and a car to be re-iced.

4. A railway icing car having a framework or superstructure on the roof thereof, said framework including an elevated ice-receiving platform, an elevator within the car operating through the roof thereof, and extending to a point above said platform, an ice-crusher connecting with and directly receiving ice deposited on said platform, said crusher having a crushed ice outlet, and a chute having one end connecting with the outlet of the crusher and the opposite end adapted to connect with the ice bunkers of an adjacent parallel car.

In testimony whereof I affix my signature in presence of two witnesses.
